[57] ABSTRACT

A power driven percussion apparatus for cracking a nut between two sockets axially aligned on a base rotating in a substantially vertical plane, one socket of relatively small mass serving as an impact member and having a short cracking stroke being driven by a hammer moving under the pull of a tension means stretched through a cam action, and the other of relatively great mass serving as an anvil and moving in response to a variation in the relationship of its aligned track to the earth's gravitational field so as to alternately approach the impact member to produce a clamping engagement of a nut to be cracked between the sockets and to move away from the impact member to allow the cracked nut to fall from between the sockets, the parts being moved by cam action and by gravity and so spaced and positioned with respect to the rotating base as to insure proper sequence and effectiveness in positioning, cracking and the discharging of a nut.

FIG. 3a

NUTCRACKER APPARATUS

This invention relates generally to improvements over nutcracker devices as set forth in my prior U. S. Pat. Nos. 3,127,917, 3,524,486, and 3,621,898. In each of these patents a nutcracker device is disclosed as including an anvil, an inertia weight, and an impact member carried by said inertia weight, all axially aligned, with the impact member after a short unrestricted stroke being limited by the inertia weight. In each is disclosed an anvil of adequate inertia to remain substantially stationary as the nut is cracked against it. In each the nut is inserted manually and, after cracking, the parts are manually separated for removal of the cracked nut. In the U.S. Pat. No. 3,127,917 the device is struck by a hand held mallet, in the U.S. Pat. No. 3,524,486 by a wooden hammer moving in a fixed track, retracted by hand against a resilient means, and in the U.S. Pat. No. 3,621,898 by a wooden hammer moving in a fixed track powered by a resilient means alternately retracted and released by a pin on a continuously moving chain powered by an electric motor.

An object of this present invention is to provide a means whereby both the movement of the anvil to engage a nut between its socket and the socket of the impact member, and the subsequent separation of the sockets to release the nut after it has been cracked, result from the action of gravity.

Another object of this invention is to provide a cam means whereby the hammer for striking the impact member is retracted against a resilient means and released during the interval that gravity, in pressing the anvil against the nut, cocks and maintains the impact member in a cocked position.

A further object of this invention is to provide a power driven base member, rotating in a substantially vertical plane, on which the anvil, the impact member, and the track for the hammer are mounted in alignment, a cam surface means disposed parallel to and spaced properly from the base member to provide mounting means for a cam surface for engagement with a pin member on the hammer so as to retract the hammer against a resilient means, the cam surface terminating so as to release the hammer for subsequent rapid motion in a primarily upward direction, to strike the impact member pressed downward by the nut, the nut being pressed down by the weight of the anvil.

A still further object is to provide a cylindrical guide means for the anvil with a port in the guide means so that a nut may be inserted therethrough for cracking between the sockets of anvil and impact member, and, after cracking, may fall from the device as further rotation separates the anvil and impact member and inverts the device so that the port comes to lie generally under the nut as anvil and impact member separate.

A still further object is to provide that one edge of such port be so positioned that a stop pin near the socketed end of the anvil will in contacting this edge limit movement of the anvil away from the impact member. In like manner, a pin near the other end of the anvil will limit the anvil's movement toward the impact member on contacting the edge of the guide means farthest from the impact member.

A still further object of the invention is the provision of a plate sloping outward from the port in the anvil guide means serving both to guide nuts into the space

between the cracking sockets and to control the direction of scatter of shell fragments.

A still further object is to provide such an apparatus wherein both the base member and cam surface means are disposed in parallel and principally vertical planes, with the cam surface lying wholly to one side of the axis of rotation and being defined by a spiral of increasing radius of curvature in the direction of rotation of the base member.

10 A still further object of the present invention is to provide such an apparatus wherein the base member is rotatable with respect to the cam surface about the axis of rotation so that, as the pin of the hammer progresses along the cam surface, the anvil tends to move and does move under gravity towards the impact member, against the nut, in turn cocking the impact member and clampingly securing the nut between the anvil's socket and that of the impact member.

A still further object is to provide for the cam surface 20 to terminate so as to release the hammer in a generally upward direction, since the anvil under gravity at this phase in its cycle will be pressing downward against the nut, insuring its clamping engagement between the sockets of anvil and impact member and insuring that 25 the impact member is cocked.

A still further object is to provide such an apparatus in which another anvil, impact member, and hammer are mounted on the base member so that with each revolution of the base member two nuts may be inserted, cracked, and discharged.

Other objects, advantages and novel features of the present invention will become apparent from the following detailed description of the invention when considered in conjunction with the accompanying drawings wherein:

FIG. 1 is a top plan view of the apparatus in accordance with the invention showing one of a pair of hammers at the commencement of its cam driven retraction from its impact member.

FIG. 1a is a partly drawn, slightly enlarged plan view, similar to FIG. 1, showing a nut resting in the socket of the anvil. Subsequent clockwise rotation will tilt the track of the anvil so that under gravity the anvil will slide towards the impact member, clampingly engaging the nut between the sockets of the anvil and the impact member.

FIG. 2 is a plan view similar to FIG. 1 showing the one hammer in the process of being retracted, its anvil moving under gravity to clamp a nut in place, and the anvil of the other nutcracking device moving under gravity away from its impact member, releasing an earlier cracked nut to fall under gravity from the device.

55 FIG. 2a is a partly drawn slightly enlarged plan view more clearly showing the details of FIG. 2;

FIG. 3 is a plan view similar to FIG. 2 showing one of the devices immediately after the hammer has moved out of contact with the cam surface and has made contact with the impact member;

60 FIG. 3a is a partly drawn slightly enlarged plan view more clearly showing the details of FIG. 3;

FIG. 4 is a sectional view taken along the line 4—4 of FIG. 1 showing the various details of the nutcracker apparatus in accordance with the present invention; and

FIG. 5, 5a and 6 are, respectively, sectional views taken along the line 5—5, 5a—5a and 6—6 of FIG. 4,

showing principally the details of structure of the extruded anvil retainer and the extruded trackway with immediately related parts, including the port in the anvil retainer, FIG. 5 and 5a having been rotated clockwise 90° to illustrate the relative position of the apparatus during use.

Turning now to the drawings wherein like reference characters refer to like and corresponding parts throughout the several views, there is shown a nut-cracker apparatus, generally designated 10, in accordance with the present invention as including a pair of percussion-type nutcracking devices 11 and 12, mounted on a base member 13 lying in a vertical or nearly vertical plane, the base member being adapted for rotation about an axis 14 perpendicular to the base member. A cam surface table 15 (see FIG. 4) is disposed slightly behind and parallel to the base member 13, and a cam surface element 16, to be hereinafter described, is mounted on the outer surface of table 15. A motor 17 is suitably mounted behind table 15 for driving a sprocket wheel 18 which in turn drives sprocket wheel 19 through a suitably provided belt 21. An axle rod 22 is mounted to the wheel 19 (see FIG. 4), and the free end of rod 22 is mounted in any convenient manner to the back of base member 13. The base member and both devices 11 and 12 mounted thereon may be therefore rotated in a clockwise direction, as shown by the arrows in the various Figures.

Since the devices 11, 12 are identical, except for their relative positions on the base member 13, only the device 11 will be described in detail. Turning to the detailed showing thereof in FIGS. 4, 5, 5a and 6, it can be seen that an anvil 23, of a solid metallic and substantially heavy mass, is guided on base member 13 by means of a cylindrical retainer 24 which is conveniently secured to the outer surface of the base member 13 by means of screws 25. Along approximately one half the length of anvil retainer 24 closest to impact member 27 a shield plate 47 slopes outward and, with the anvil to the left of the axis of rotation, upward. That portion of the cylindrical anvil retainer 24 behind shield plate 47 has been removed, leaving a port 49 for insertion of a nut between the sockets 34 and 35. FIG. 5a is a section through this port showing the absence of that part of anvil retainer 24 behind plate 47, and how a nut may easily be dropped through the port for cracking. Obviously one half turn later the port will face downward, to allow a (cracked) nut to fall out after separation of sockets 34 and 35. Anvil 23 is provided with outwardly extending stop pins 26 near its opposite ends for engagement with the opposite ends of the complete cylindrical segment of retainer 24 to thereby limit movement of the anvil toward and away from the impact member 27 which is guided within a guide bearing 28 mounted on the base member 13. The impact member 27 comprises a generally cylindrical connecting portion, or shank, 29 which is suitably disposed and guided through the bore of guide bearing 28. Enlargements 31, 32 at the opposite ends of shank 29 limit the rectilinear movement of the impact member in either direction through the guide, and their spacing thereby determines the length of an unrestricted cracking stroke which may be given by the impact member. The length of the stroke may be further restricted, if desired, to prevent over-cracking, by suitable washers 33, on shank 29 between the enlargement 32 and the bearing 28. To cushion the impact between enlargement 32 and

bearing 28, at least one resilient washer should always be included.

The mutually facing ends of the anvil and the impact member are provided with sockets 34 and 35, respectively, which are adapted for reception between them of a nut N to be cracked, as shown in the drawings.

A hammer 36 is provided for delivering a blow to the impact member and may simply comprise an elongated block of wood of rectangular cross-section which is guided for longitudinal movement on the base member in a suitable trackway 37 which may simply comprise a length of extruded aluminum track including relatively opposed horizontal and vertical wall portions 38 and 39, respectively, together with a horizontally extending wall 41 secured to the base member in the normal manner as by screws 42. For urging the hammer into impacting engagement with impact member 27 one or more rubber bands 43 or other type resilient means, are stretched between pins 44 and 45 projecting outwardly from the hammer and from the outer surface of the base member, respectively.

To retract hammer 36 away from impact member 27, a depending cam pin 46 is provided near the rearward end of the hammer, so that as the device 11 is rotated clockwise to its position shown in FIG. 1, pin 46 will commence sliding engagement with surface 16a of the cam surface member 16 to thereby progressively move the hammer 36 away from impact member 27. This progressive movement is brought about by reason of surface 16a being defined by a spiral of increasing radius in the direction of rotation.

Before proceeding with a detailed description of the nutcracker operation, it should be pointed out that the device 12, which, as mentioned above, is identical in all respects to the nutcracker device 11, is located on the base member 13 in such a manner that its anvil 23' lies substantially adjacent the impact member 27 of the device 11, while the impact member 27' thereof lies substantially adjacent anvil 23 of the device 11. This overlapping parallel position is for conservation of space in using two devices on base member 13, but it is recognized that devices 11 and 12 may be located in other positions and that two or more of such devices may be arranged radially from the axis of rotation or along the sides of a triangle or square or in other patterns without departing from the spirit of the invention.

With reference first to device 11 and FIGS. 1 and 1a of the drawings, it can be seen that pin 46 of hammer 36 has just been brought into contacting engagement with surface 16a of cam element 16 during clockwise rotation of base member 13 about the axis of rotation 14. During such disposition of the device 11, the anvil 23 is in a position farthest from impact member 27 after having slid into such position under gravity. Its forward stop pin 26, bearing against the edge of the cylindrical section of retainer 24, prevents anvil 23 from moving outwardly therefrom. It should also be pointed out that shield plate 47, extending the length of the port 49 in retainer 24, slopes upward and forwardly, as seen most clearly in FIGS. 4, 5 and 5a. When the device 11 is in its position of FIG. 5a the operator may place a nut N on plate 47 to roll through the port 49 in anvil retainer 24 into the cracking space defined by anvil 23, retainer 24, impact member 27, and base member 13, or he may manually place the nut directly into this space, whereupon the nut will simply come to rest against the lower most portion of anvil retainer 24. The

nut may slide into the socket 34 of anvil 23 if the device is tilted enough in that direction, as in FIG. 1. It is not necessary that the nut be inserted at these early stages; indeed it may be inserted at any time after these stages and before rotation to and beyond a horizontal position has occurred enough to tilt the track of anvil 23 so that gravity pulls anvil 23 towards impact member 27.

With reference to FIG. 2, it can be seen that the base member 13 has been rotated beyond its horizontal position, so that anvil 23 of device 11 has been moved under gravity in a forward direction towards impact member 27, producing clamping engagement of the nut N between the sockets 34 and 35, and pushing the impact member enlargement 31 into engagement with guide bearing 28. The impact member 27 is now in a cocked position since the enlargement 32 and the washers 33 are together spaced a slight distance from guide bearing 28. Also in this position of FIG. 2, hammer 36 has been moved completely away from enlargement 32 (see FIG. 2a).

As the base member continues its clockwise rotation, pin member 46 of hammer 36 approaches and moves beyond edge 16b of cam surface 16, and, as shown in FIG. 3, hammer 36 moves under the action of resilient means 43 toward and into impacting engagement with impact member 27, whereupon socket 35 is thrust upon nut N, cracking it. Enlargement 32 with its washers 33 is moved forwardly into engagement with guide bearing 28, limiting the cracking movement so as not to compress the meat of nut N. Further rotation past the horizontal position tilts the anvil retainer 24 so that the anvil 23 under gravity moves away from impact member 27, releasing the cracked nut to fall from the device, as is shown in FIGS. 2 and 2a, with cracked nut N', falling from the device 12, shown shortly after passing through port 49'.

If the base member 13 is in the position shown in FIG. 1, and no nut is inserted into the space between sockets 34 and 35, further rotation results in the retainer 24 of anvil 23 becoming horizontal and then tilted so that anvil 23 under gravity slides toward impact member 27, until its motion is arrested by rearward stop pin 46 contacting the edge of the cylindrical section of anvil retainer 24, farthest from impact member 27, effectively preventing subsequent damaging impacting engagement between impact member 27 and anvil 23. In FIG. 1 this limited approach is clearly illustrated by the position of anvil 23'.

When base member 13 has rotated 180° beyond the position shown in FIG. 1, the events described above for device 11 occur in the same sequence for corresponding parts of device 12. Thus in the arrangement shown here, each device is 180° ahead of (or behind) its mate, and thus two nuts may be inserted, cracked, and discharged with each rotation of base member 13.

The positioning of base member 13 in a substantially vertical plane allows for the use of gravity in effecting anvil movement and discharging cracked nuts. It is readily apparent that forces other than gravity, such as magnetic forces or simple mechanical forces, may be utilized for this same end, allowing for transposition to a horizontal plane and allowing for the base member to be stationary with the cam elements rotating.

The manner in which the nuts are placed between the socketed ends of each device forms no part of the present invention, although it should be noted that place-

ment may be carried out by hand or by some suitable conveyor or other similar means.

From the foregoing description, it will be readily apparent that the various components used in assembling the present apparatus are simple in their design and are easily obtainable, and may be assembled without difficulty into a nutcracking apparatus which quickly and effectively serves to crack nuts without crushing of the nut meat.

Obviously, many modifications and variations of the present invention are possible in the light of the above teachings. It is therefore to be understood that within the scope of the appended claims, the invention may be practiced otherwise than as specifically described.

What is claimed is:

1. Nutcracker apparatus comprising a base member, at least one percussion-type device for the cracking of nuts, comprising an anvil and an impact member, each guided on said base member for relative rectilinear movement in alignment with the other, each said anvil and said impact member having a socketed end facing its aligned counterpart for clamping reception therebetween of a nut to be cracked, means on said base member and on said impact member restricting the rectilinear movement of said impact member to a predetermined range, a hammer guided on said base member for movement in alignment with said impact member, means for guiding said anvil, resilient means interconnecting said hammer with said base member and urging said hammer toward said impact member, cam surface means parallel to and spaced from said base member, a cam surface of variable radius on said cam surface means, a pin member on said hammer disposed for cooperative engagement with said cam surface for movement away from said impact member thereby, and means for imparting relative rotation between said base member and said cam surface about a common axis whereby said hammer is moved away from said impact member against the action of said resilient means during engagement between said pin member and said cam surface, and whereby said hammer is moved out of engagement with said cam surface, thereby cracking a nut clamped between said socketed ends.

2. The apparatus according to claim 1 wherein said base member and said cam surface means lie in parallel substantially vertical planes and wherein said cam surface lies wholly to one side of the axis of rotation and is defined by an arc having a variable cam radius.

3. The apparatus according to claim 2 wherein said base member is rotatable with respect to said cam surface means about the common axis so that, upon rotation of said base member, said means for guiding said aligned anvil tilts so that under gravity said anvil moves slidingly toward said impact member to clampingly engage a nut between said socketed ends, and to displace said impact member to one extreme of its predetermined range, thereby cocking it for cracking the engaged nut.

4. The apparatus according to claim 3 wherein said cam surface has an edge to facilitate release of said hammer during rotation of said base member for subsequent movement under the pull of said resilient means toward and into impacting engagement with said impact member during the interval that a nut is clampingly engaged between the said socketed ends as a result of movement of said anvil under gravity toward said impact member whereby the nut is cracked, and

whereby further rotation of said base member beyond a horizontal position tilts the means for guiding said anvil so that said anvil under gravity moves slidily away from said impact member, releasing the cracked nut to fall from between said socketed ends.

5. The apparatus according to claim 4 wherein said anvil guide means is provided with a port so positioned that prior to movement of said anvil toward said impact member a nut will pass through said port under gravity for subsequent clamping engagement between said socketed ends for cracking and, upon subsequent rotation of said base member, will be so positioned as to allow passage of said nut after cracking in falling under gravity from the device.

6. The apparatus according to claim 1 wherein two of said devices are provided side by side on said base member, and wherein opposite ends of said devices are adjacent so that each said device is one half cycle ahead of (or behind) the other and wherein corresponding parts of said two devices are symmetrically located about the axis of rotation of said base member.

7. The apparatus according to claim 5 wherein said anvil is provided with stop pins near its opposite ends for engagement with opposed edges on said anvil guide means to thereby limit movement of said anvil toward and away from said impact member.

8. The apparatus according to claim 6 wherein each of said anvils is provided with stop pins near its opposite ends for engagement with opposed edges on its associated anvil guide means to thereby limit movement of each said anvil toward and away from its respective

impact member.

9. The apparatus according to claim 5 wherein said guide means is provided with an outwardly open shield plate extending toward said impact member to substantially span the distance between said socketed ends, thereby serving both to guide the nut into the space between said socketed ends and to limit the area of scatter of shell fragments.

10. The apparatus according to claim 6 wherein each of said devices is provided with a port so positioned that prior to movement of each said anvil toward its impact member a nut will pass through its respective port under gravity for subsequent clamping engagement between said socketed ends of each said device and, upon 15 subsequent rotation of said base member, will be so positioned as to allow passage of said nut after cracking in falling under gravity from each said device.

11. The apparatus according to claim 6 wherein said guide means for each said anvil is provided with an outwardly open shield plate extending towards its respective impact member to substantially span the distance between said respective socketed ends of each said device, thereby serving both to guide nuts into the space between said socketed ends and to limit the area of scatter of shell fragments.

12. The apparatus according to claim 1 wherein said base member lies in a substantially vertical plane so that as a complete rotation of said base member tilts the means for guiding said anvil, said anvil under gravity alternately approaches and moves away from said impact member to clampingly engage and release a nut.
